LUGGAGE CASE OR SIMILAR ARTICLE

Steven S. Feinberg, 28 Linden Drive, Providence, R.I.

Filed June 26, 1963, Ser. No. 75,522

Term of patent 14 years

(Cl. D87—5)

FIG. 1

FIG. 3

FIG. 1 is a front elevational view of a luggage case or similar article, embodying my new design;

FIG. 2 is a side elevational view looking from the right of FIG. 1; and

FIG. 3 is a top plan view thereof.

The dominant features of my design reside in the portion shown in full lines.

I claim:

The ornamental design for a luggage case or similar article, as shown and described.
